Wm. C. Clapp
Albert F. Hellings

UNITED STATES PATENT OFFICE.

LOUIS HASSELBUSCH, OF PHILADELPHIA, PENNSYLVANIA.

CARRIER OR CONVEYER.

1,102,913.

Specification of Letters Patent.

Patented July 7, 1914.

Application filed January 29, 1914. Serial No. 815,161.

To all whom it may concern:

Be it known that I, LOUIS HASSELBUSCH, a citizen of the United States, residing in Philadelphia, county of Philadelphia, State 5 of Pennsylvania, have invented a new and useful device or improvement in carriers or conveyers especially adapted for and to be used in raising and lowering shades and conveying them from one location to another, 10 of which the following is a full, clear, and exact description.

The object or purpose of this invention is to provide a carrier or conveyer to receive, hold, retain and be adjusted to any length of 15 rod or bar made of wood or metal, to so construct the carrier or conveyer that by its novel construction a rod, bar, window shade or map can be immediately attached to it, be retained by it, and firmly and securely 20 held in place.

Another purpose of the invention is to provide a carrier or conveyer which when adjusted to and carried by it, a rod, bar, shade roller, or map can be conveyed from 25 one location to another, raised or lowered at will in an easy, simple and efficient manner.

Another object of the invention is to provide a means whereby, when the carrier or conveyer is attached to a window frame, 30 carrying a shade, means are provided whereby the shade can be raised or lowered, from the top or bottom at will, permitting the free and uninterrupted passage of air and light, also to exclude drafts especially in the 35 rooms and wards of hospitals and homes.

The invention consists in a novel construction and combination of the several parts, as will hereinafter be fully set forth and pointed out in claims.

Reference is to be had to the accompanying drawings, forming a part of this specification in which similar characters of reference indicate corresponding parts in all 40 the figures.

Figure 1. is a vertical section through the casing of the device, illustrating the parts contained within the casing in a side elevation. Fig. 2. is a view of the improved device as applied and attached to window 45 frame. Fig. 3. is a vertical transverse section taken practically on the line A. of Fig. 1. Figs. 4 and 5 are horizontal and vertical sections, respectively, of one of the two elbows or right-angular supports for 50 the curtain-bar or roller. Figs. 6 and 6^a are

different views of a hook to which the curtain suspending cord is attached. Fig. 7 illustrates how the device may be carried by hand.

In Figs. 1 and 2, numerals 1 and 2 indicate tubes which are telescopically connected, the larger one having also a collar 3 whose contracted end embraces the smaller tube 2, and thus supplements the telescopic joint proper. Below and parallel to the telescopic member thus formed is a curtain-bar or roller 10, and the means for suspending the latter from the telescopic member are two elbow or right-angular brackets 5. The horizontal portions or arms of these elbows or brackets are connected by a spiral spring 4, which is attached to their reduced ends 7, and is extended in the middle portion of the telescopic tube. The ends of the curtain-bar or roller 10 rest in inclined, open 60 sockets 9 (see Figs. 1 and 5) which are formed in the inner sides and lower ends of the vertical members of the elbows or brackets. Thus the said bar or roller is adapted to be conveniently inserted or detached, as will be readily understood.

The entire device may be suspended by cords, which may be attached in different ways, thus, as shown in Figs. 1 and 4, cords 11 may pass through holes 6 formed in the outer ends of the telescopic members and coincidentally in the horizontal arms of the brackets 5; or the cords 11^a may be passed through holes 8 formed in the outer upper angles of the brackets.

The operation of the device is obvious. The slideable tubular members 1 and 2 are adjusted telescopically according to the length of the curtain-roller 10, and the tension of the spring 4 will cause brackets 5 85 to press lightly against the ends of the roller.

Screw hooks 12, having curved free ends 13 may be employed for supporting the cord 11^a, or the cord may be attached to the hook for holding the curtain conveyer supported 100 at any required height.

The vertical members of the brackets 5 may be provided with wheels 14 to relieve friction with a sash or window-frame when the curtain is being adjusted higher or 105 lower.

What I claim is:—

1. A conveyer and support for window shades comprising an adjustable tubular member, brackets applied to the ends of said 110

member and having sockets for reception of a shade roller, and a spring connecting said brackets, as described.

2. A conveyer and support for window shades comprising telescoped tubes, right angular brackets whose horizontal arms enter the outer ends of the tubes, a spring arranged in the telescoped tubes and connecting the said brackets, the vertical or pendant arms of the brackets having their lower

ends provided with open slots serving as sockets for reception of a curtain-roller, as described.

In testimony whereof I have signed this specification in the presence of two witnesses.

LOUIS HASSELBUSCH.

Witnesses:

ALBERT F. HELBLING,
J. C. CLAGHORN.
